UNITED STATES PATENT OFFICE.

JOSEPH O. CADIEUX, OF MERIDEN, CONNECTICUT, ASSIGNOR TO THE CONNECTICUT
TELEPHONE & ELECTRIC COMPANY, INCORPORATED.

ELECTRIC SIGNAL SWITCH.

Application filed January 10, 1925. Serial No. 1,536.

To all whom it may concern:

Be it known that I, JOSEPH O. CADIEUX, a citizen of the United States of America, residing at Meriden, county of New Haven, State of Connecticut, have invented a new and useful Electric Signal Switch, of which the following is a specification.

My invention relates to improvements in switches of the type of my former Patent 1,473,591 and this application is a partial continuation of application No. 648,213 filed June 28th, 1923, now Patent No. 1,527,026. All of these switches are intended particularly for use in annunciator or call systems such as are frequently used in hospitals and the like. My first invention was directed to a pull type of switch and contains a catch and release device applicable as well to push button switches. My second invention related more particularly to a push button type of switch but also embodies a central guide and auxiliary signal feature applicable not only to push button but to pull switches. My present invention is directed toward improvements in the pull switch type of device embodying the auxiliary signal mechanism and also simplified latching and releasing mechanism. This application also claims specifically one form of auxiliary switch mechanism divided out of said application No. 648,213. I have also shown herein certain features of the invention as applied to a push button switch embodying improvements in the mechanism of my former application with an improved method of latch release.

Fig. 1 is a side view and partial section showing one form of my invention as applied to a pull switch and showing the parts in the normal open circuit position.

Fig. 2 is an enlarged longitudinal sectional view showing the parts in the position they would occupy with the normal signal energizing circuit closed.

Fig. 3 is a sectional view on the plane of the line 3—3 of Fig. 2.

Fig. 4 is a side view and partial section showing the parts in the position they occupy when sending an auxiliary, supplemental or emergency signal.

Fig. 5 is a plan view of one form of the invention as embodied in a push button type switch.

Fig. 6 is a longitudinal section and side view of the device of Fig. 5.

Fig. 7 is a transverse sectional view on the plane of the line 7—7 of Fig. 6 drawn on the scale of Fig. 5.

Fig. 8 is a sectional view of the switch mechanism of Fig. 6 with the parts in the closed circuit position.

Fig. 9 is a rear end view of the parts shown in Fig. 8.

Fig. 10 is a longitudinal, sectional view and partial side elevation showing a modification.

Fig. 11 shows another slightly different modification copied from my former application 648,213.

The construction shown in Fig. 1 is what is sometimes called a ward station which has a plate 15 adapted to be secured to the wall or to an outlet box in the wall. This form of device has a local signal light 16 which, however, is not involved in the invention herein claimed. The switch proper has an insulating base 17 which is secured to the back of the face plate 15 by means of a U-shaped frame 18. A series of spring contact fingers such as 19, 20 and 21 are secured in grooves in the insulating base 17 and provided with suitable binding posts or terminals such as 22, 23 and 24. Any number of these contact fingers may be employed and a suitable signal device such as a lamp 25 will be arranged in circuit with each.

Embedded or secured in the insulating block is a central guide pin 26 having a circuit terminal or binding screw 27 at the rear. The spring contact finger 28 is similar to the other spring contact fingers and is secured in a groove in the insulating base 17 in contact with a member 29 which is connected with a plate 30 on the front of the base 17. This plate 30 is in electrical connection with a part of the guide pin 26.

On top of the shank of the spring contact finger 28 but insulated from it I secure an auxiliary contact member 31 which is provided with a circuit terminal or binding post 32. In circuit with this member is the emergency buzzer or other auxiliary signal device 33.

Mounted to slide on the guide pin 26 is an insulating member 34 which carries a contact member 35 which may be secured on to the shank of the member 34. Behind the contact ring 35 is an insulating washer 36 which projects outwardly beyond the pe-

iphery of the contact ring 35 so as to form a shoulder adapted to coact with parts of the spring contact fingers as shown in Fig. 4. This insulating washer may be held in place by a nut 37. The sliding member 34 is provided with an operating stem 38 to which is secured the pull chain 39 the chain being guided in the eyelet 40 in the face plate 15. A spring 41 is interposed between the rear of the face plate and the cone 42 on the stem 38 so as to normally tend to push the stem 38 and the contact carrier rearwardly and yieldingly oppose the operation of the chain 39. A sliding latch 43 is guided in the frame 18 and adapted to engage the rear of the cone 42 when the cone is pulled forwardly. The latch 43 is normally pressed upwardly by a spring 44 so that the lower inside edge of the latch is in the path of movement of 20 the lower edge of the cone 42. When the cone is pulled forwardly its lower incline surface pushes down the latch and when the cone passes entirely through the latch the spring 44 pushes the latch up into the path 25 of movement of the cone 42 as shown in Fig. 2, so as to hold the cone and the attached parts in the forward position. In order to retract the latch I provide an arm 45 which engages the upper end of the latch as shown 30 in Fig. 1. This arm projects through the face plate and is provided with a finger piece 46 immediately above the chain 39. The chain or cord thus provides a simple means for operating the switch and the release finger piece 46 provides a convenient 35 method of restoring the switch to its normal open circuit position. It will be seen that the two operating members 39 and 46 are so different in construction and in operation 40 that there is no danger of accidentally releasing the latch when pulling the switch and vice versa. There is no danger of turning on the switch when trying to release it.

When the switch is pulled on the parts 45 occupy the position shown in Fig. 2 at which time we can trace the circuit through the lamp 25 to the terminal 23, spring finger 20, contact ring 35, spring finger 28, members 29 and 30, pin 26, circuit terminal 27 and the 50 source of energy (not shown). When the switch has been set in this position by the operator, presumably a patient in the hospital, the switch stays set and the light or 55 lights on. The switch is supposed to stay in this position until the attendant comes to the station and releases the switch by pressing on the finger piece 46.

In case the patient is particularly anxious 60 to have immediate attention or to especially attract the attention of the superintendent or attendant at whose station the buzzer or alarm device 33 is located it is simply necessary to pull a little harder on the chain and draw out the contact slide to the position 65 shown in Fig. 4 at which time the shoul-

dered washer 36 moves the spring contact finger 28 into engagement with the contact member 31. The circuit through the buzzer then passes through the terminal 32 to the member 31, spring finger 28, parts 29 and 30, 70 guide pin 26 and circuit terminal 27.

The construction is also so arranged that the insulating shoulder 36 can retract all of the spring fingers 28, 19, 20 and 21 from the contact ring 35 at the same time so as to simultaneously open all the circuits which were established in the position shown in Fig. 2. When the parts are in the position shown in Fig. 2 it is therefore possible for the patient by repeated pulling on the chain 80 or operating cord to flash all the signal lights thus making a special signal to attract the attention at all of the stations where the signal lights are located. In fact it will be noted that in the position of the contact member intermediate the position shown in Figs. 2 and 4 all the lights will be out before the emergency or buzzer signal is energized.

In the form shown in Figs. 6, 7 and 8 the insulated base 50 carries the central guide 90 pin 51 for the contact member and also spring contact fingers such as 52 and 53 and the auxiliary contact member 54. In this case the sliding member consists of an insulating portion 55, a contact ring 56 and the shouldered insulating washer 57 intended to retract the contact fingers from the ring 56 and force the finger 53 into engagement with the contact member 54. The member 58 electrically connects the guide 100 pin 51 and the contact finger 53. In this case the spring 59 is interposed between the contact member and the base so as to normally push the contact member away from the base instead of toward it. The contact member is also provided with a push button 60 instead of a pull cord or chain. The frame 61 is similar to the frame 18 only in this case it is secured to the face plate 62 which has a flange 63 which fits in the mouth of the tubular casing 64 and is secured in place by one or more screws 65. The latch member 66 is guided in the frame 61 and normally under the pressure of the spring 67 which holds it in position with one end 68 in a slot 69 in one wall of the tubular casing 64. The wall of the casing around the slot 69 is drawn inwardly as shown in Figs. 6 and 7 so as to come in contact with one arm of the frame 61 and close the opening which would otherwise exist at this point. The contact member carries the cone 70 adapted to interlock with the latch slide 66.

The circuit is closed through the switch 125 by pressing on the button 60 and the latch 66 thereupon automatically engages the shoulder of the cone 70 and holds the switch in the closed circuit position unless the push button 60 is pushed in a little further so as 130

to retract the fingers 52 and 53 from the contact ring 56 which of course would put out the lights. When the button 60 is pushed in a little further the auxiliary buzzer or emergency circuit is completed through the contact member 53. When the attendant wishes to release the switch and stop the signals it is simply necessary to press on the end 68 of the latch slide with the finger nail as shown in Fig. 7. These parts are so designed and constructed that it is practically impossible to accidentally release the latch. Nevertheless the device does not require any special key or tool for releasing the latch since the operation may easily be performed by the tip of one finger pressed into the slot 69.

In the construction shown in Fig. 10 the emergency circuit is completed from the center contact pin 72 through the contact 73 in the end of the sliding member 74 thence through the spring 75 to the plate 76 and terminal 77 when the slide is pushed in until the contact 73 engages the end of the guide pin 72.

In the construction shown in Fig. 11 the spring contact finger 80 has a projection 81 at the rear electrically connected with the guide pin 82 which serves as one circuit terminal. The other circuit terminal 83 is connected to the contact member 84. The slide 85 on the pin 82 is adapted to engage a shoulder 86 on the contact finger 80 and force the tip of the finger 80 into contact with the member 84.

I claim:

1. A signal switch comprising an insulating base, a guide pin extending through said base, a binding screw in the rear end of said pin, a contact plunger slidable on the front end of said pin, a bracket having an arm extending along one side of said base and having another arm extending along the front of said base and contacting with said pin, and a spring arm contact secured outside of the side arm of said bracket and engaging said contact plunger.

2. In a switch, a base, a spring contact finger carried thereby, a center terminal and guide electrically connected thereto, a reciprocable insulating member having a contact member adapted to engage said spring contact finger and an insulating shoulder adapted to disengage said finger and a stationary contact adapted to be engaged by said finger.

3. In a switch, an insulating base, a plurality of contact fingers projecting therefrom, an insulating member slidable between said fingers, a contact member carried thereby to engage said contact fingers, an operating member connected to said insulating member, an auxiliary contact and means carried by said insulating member for moving one of said fingers away from said con-

tact member and into contact with said auxiliary contact.

4. In a switch, a base, a plurality of contact fingers projecting therefrom, an insulating member slidable between said fingers, a contact member carried thereby to engage said fingers, a face plate, an operating members connected to said insulating member and guided in said plate, an auxiliary contact adapted to be engaged by one of said contact fingers, and means carried by said insulating member for moving said latter finger away from said contact member and electrically contacting it with said auxiliary contact.

5. A signal switch comprising an insulating base, a guide pin projecting therefrom, a plunger slidable on said pin, a contact member carried by said plunger, spring contact arms carried by said base and having ends which normally press upon said plunger, an auxiliary contact mounted adjacent one of said arms, said plunger having a shoulder adapted to move all of said contact arms away from said contact member and adapted to force one of said arms into engagement with said auxiliary contact after said arms have been moved away from said contact member.

6. In a switch, an insulating base, a stationary guide pin projecting therefrom, a spring arm contact carried by said base at one side of said pin, a stationary contact adjacent said arm, a plunger reciprocable on said pin, a contact carried by said plunger and adapted to engage said spring arm contact and a flange carried by said plunger and adapted to engage said arm contact and force it against said stationary contact.

7. In an electric switch, an insulating base, a guide pin projecting forwardly therefrom, a U-shaped frame having side bars secured to said base, a face plate at the opposite end of said frame, a contact carrying plunger slidable upon said pin and having an operator extending through said face plate and a conical spring having its large end pressing against said face plate and its small end pressing against said plunger.

8. In a switch, an insulating base, a central terminal and guide, a plurality of light contacts, a main movable contact member for connecting said light contacts, an auxiliary lateral buzzer contact, one of said light contacts being laterally movable away from said movable contact and connected to said central terminal and means for moving said movable member on said guide toward said light contacts and for moving said laterally movable contact away from said main movable contact member and into engagement with said buzzer contact.

9. In an electric switch, an insulating base, a guide pin projecting therefrom, a

- spring arm contact secured to one side of said base, a stationary contact adjacent said spring arm contact, a plunger reciprocable on said guide pin, a contact member carried by said plunger and adapted to engage such spring arm contact, and a projecting flange carried by said plunger for engaging said spring arm contact and moving it away from the co-acting contact on said plunger and into electrical engagement with said stationary contact. 10
11. In an electric switch, an insulating base, a face plate, longitudinally extending side bars connecting said face plate to said base, spring contact fingers projecting from said base towards said face plate, a plunger having a contact reciprocable between said contact fingers, a latch plate co-acting with said plunger and having its opposite ends guided in said side bars, a spring operating arm secured to said base adjacent one of the side bars and having one end engaging said latch plate and a release arm secured on the outside of the other side bar and having an operating tip projecting through said face plate. 20 25 30 35
10. In an electric switch, an insulating base, a guide embedded in said base and having one end projecting therefrom and a binding screw at the opposite end, a spring arm contact secured to one side of said base and having a binding screw accessible at the side, a plunger guided on said pin and having a contact for engagement with said

JOSEPH O. CADIEUX.
